US00D724059S

(12) **United States Design Patent**
Kim

(10) **Patent No.:** **US D724,059 S**
(45) **Date of Patent:** **** Mar. 10, 2015**

(54) **REMOTE CONTROLLER**

(71) Applicant: **Samsung Electronics Co., Ltd.,**
Suwon-si (KR)

(72) Inventor: **Ki-Soo Kim**, Gunpo-Si (KR)

(73) Assignee: **Samsung Electronics Co., Ltd.,**
Suwon-si (KR)

(**) Term: **14 Years**

(21) Appl. No.: **29/466,857**

(22) Filed: **Sep. 12, 2013**

(30) **Foreign Application Priority Data**

Mar. 12, 2013 (KR) 30-2013-0012538

(51) **LOC (10) Cl.** **14-03**

(52) **U.S. Cl.**

USPC **D14/218**

(58) **Field of Classification Search**

USPC D10/70, 65; D13/154, 153, 168, 133;
D14/218, 205, 155, 225, 226, 247;

(57) **CLAIM**

The ornamental design for a remote controller, as shown and described.

DESCRIPTION

FIG. 1 is a top rear perspective view of a remote controller showing my new design;

FIG. 2 is a left-side view thereof;

FIG. 3 is a right-side view thereof;

FIG. 4 is a rear view thereof;

FIG. 5 is a front view thereof;

FIG. 6 is a top view thereof; and,

FIG. 7 is a bottom view thereof.

The broken lines are for illustrative purposes only and form no part of the claimed design.

1 Claim, 4 Drawing Sheets
